Primary Examiner—Alan P. Douglas*Assistant Examiner*—J. H. Musgrave*Attorney, Agent, or Firm*—Pearne, Gordon, McCoy & Granger[57] **CLAIM**

The ornamental design for a vibration isolator, as shown and described.

DESCRIPTION

FIG. 1 is a top view of a vibration isolator showing my new design;

FIG. 2 is a bottom view of the same;

FIG. 3 is a perspective top view of the same;

FIG. 4 is a perspective bottom view of the same;

FIG. 5 is a vertical projection of the front side of the same;

FIG. 6 is a vertical projection of the rear side of the same;

FIG. 7 is a vertical projection of the left side of the same; and,

FIG. 8 is a vertical projection of the right side of the same.
